United States Patent Office

Des. 188,257
Patented June 21, 1960

188,257

COUNTING DIAL

Joseph Palma, Jr., River Forest, Ill., assignor to Am-
phenol-Borg Electronics Corporation, Broadview, Ill.,
a corporation of Delaware

Filed Sept. 21, 1959, Ser. No. 57,614

Term of patent 14 years

(Cl. D52—1)

Fig. 1 is a front elevation of a counting dial embodying my new design.

Fig. 2 is a side elevation on an enlarged scale of the counting dial shown in Fig. 1.

Fig. 3 is an enlarged perspective view of the counting dial shown in Figs. 1 and 2.

Fig. 4 is an elevation of the counting dial looking from the right of Fig. 2.

I claim:
The ornamental design for a counting dial, as shown.
